(57) **CLAIM**

The ornamental design for hitch step, as shown and described.

DESCRIPTION

FIG. 1 is a perspective view of the hitch step according to the present invention, from an upper, front perspective.

FIG. 2 is a perspective view of the hitch step according to the present invention, from a lower, rear perspective.

FIG. 3 is a top plan view of the hitch step.

FIG. 4 is a lower plan view of the hitch step.

FIG. 5 is a front elevation view of the hitch step.

FIG. 6 is a rear elevation view of the hitch step.

FIG. 7 is a left side elevation view of the hitch step.

FIG. 8 is a right side elevation view of the hitch step; and,

FIG. 9 is a view of the hitch step mounted on a hitch receiver of a pickup truck.

Structure, environment, and/or boundaries shown in broken lines form(s) no part of the claimed design.

1 Claim, 9 Drawing Sheets
